 Shakir Law PLLC(57) **CLAIM**

The ornamental design of a sensor relay, as shown and described.

DESCRIPTION

FIG. 1 is a front isometric view of the sensor relay,
 FIG. 2 is a rear isometric view of the sensor relay,
 FIG. 3 is a bottom-rear isometric view of the sensor relay,
 FIG. 4 is a front view of the sensor relay,
 FIG. 5 is a left-side view of the sensor relay,
 FIG. 6 is a right-side view of the sensor relay,
 FIG. 7 is a rear view of the sensor relay,
 FIG. 8 is a top view of the sensor relay; and,
 FIG. 9 is a bottom view of the sensor relay.
